United States Patent Office

Des. 223,973
Patented June 20, 1972

223,973

ILLUMINABLE MAKEUP MIRROR OR SIMILAR ARTICLE

Edward A. Irelan, Lombard, Ill., assignor to Sunbeam Corporation, Chicago, Ill.

Filed July 9, 1970, Ser. No. 24,219

Term of patent 14 years

Int. Cl. D28—03

U.S. Cl. D86—10

Fig. 1.

Fig. 2.

Fig. 3.

Fig. 4.

Fig. 5.

FIG. 1 is a perspective view of an illuminable makeup mirror showing my new design;

FIG. 2 is a side elevational view thereof;

FIG. 3 is a top view thereof taken along the line 3—3 of FIG. 2;

FIG. 4 is a rear view thereof taken along the line 4—4 of FIG. 2; and

FIG. 5 is a vertical sectional view along the line 5—5 of FIG. 1.

I claim:

The ornamental design for an illuminable makeup mirror or similar article, substantially as shown.
